UNITED STATES PATENT OFFICE.

AMANDUS C. ROESSLER, OF MINEOLA, NEW YORK.

IGNITER.

1,148,409.

Specification of Letters Patent. Patented July 27, 1915.

Application filed October 13, 1914. Serial No. 866,472.

To all whom it may concern:

Be it known that I, AMANDUS C. ROESSLER, a subject of the King of Great Britain, residing at Mineola, in the county of Nassau 5 and State of New York, have invented new and useful Improvements in Igniters, of which the following is a specification.

The general object of this invention is to facilitate the operation of lighting the various burners of a gas stove without the use of a match or other fire producing means. And to this end the invention consists in mounting on a gas stove a gas lighting device comprising a horizontally arranged 15 torch which is connected with the gas supply and in providing a means for turning the torch, which when lighted is arranged for directing the flame into communication with the burner.

Other objects will appear and be better understood from that embodiment of my invention of which the following is a specification, reference being had to the accompanying drawings, forming part hereof, in 25 which:

Figure 1, is a diagrammatic plan view of a gas stove showing the device in operative position thereon. Fig. 2 is an enlarged detail side elevational view of the device. Fig. 3 is a vertical cross sectional view of the torch end of the device taken on the line 3—3 of Fig. 2 but showing the torch swung around to its operative position. Fig. 4 is a horizontal cross sectional view taken on the line 4—4 of Fig. 3 showing the valve in 35 its open position. Fig. 5 is a view similar to Fig. 4 but showing the valve in its closed position. Fig. 6 is a view of the torch end of a modified form of device showing a means for automatically igniting the torch. Fig. 7 is a sectional view of a portion of the device showing a modified form of torch. Fig. 8 is an end elevational view thereof. Fig. 9 is a plan view of the torch end of a 45 modified form of device showing a means for cleaning the torch tip. Fig. 10 is a diagrammatic plan view of a three burner gas stove showing the invention applied thereto, and Fig. 11 is a view of the torch showing 50 a still further modified form of means for igniting the same.

Referring to the drawings in detail 1 designates a gas stove provided with the usual burners 2 which are connected by the

pipes 3 with a manifold 4 which connects 55 with a gas supply pipe 5.

My improved device for igniting the gas burners is indicated as at 6 and consists of a cylindrical valve casing 7 which is centrally bored as at 8 to receive a tapering 60 plug or valve 9. The upper end of the plug is provided with a screw threaded opening 10 to receive the exteriorly threaded inner end of a laterally projecting tubular torch 11. The outer end of the torch is also exteriorly threaded as at 12 so as to receive a sleeve 13 in which is fitted an adjustable burner tip 14 through whose aperture the gas is discharged.

The plug is provided with an axial bore 70 15 which connects at its upper end with the torch 11 and has its lower end communicating with a channel 16 located approximately at the central portion of the plug. The channel 16 may if desired be made of such 75 a length that when the valve is in its closed position the supply of gas to the torch may be entirely shut off and the torch automatically lighted when the device is actuated as will be hereinafter described.

By providing a small groove in the side 80 of the plug, as indicated at 16' for communicating with the channel 16 as indicated in Figs. 4 and 5 communication is established 85 between the gas supply and the torch, whereby when the valve is in its closed position as indicated in Fig. 5, a small supply of gas is permitted to escape to the torch for maintaining the burning of a pilot light at the tip thereof.

The valve casing is provided with a laterally projecting tubular extension 17 which through a pipe 18 is connected to the manifold of the gas stove. The extension and pipe serve as a conduit to convey the gaseous fluid from the supply to the torch. By means of a bracket 18' the valve casing is suspendingly connected to the under side of the top plate of the gas stove, a bolt 19 serving as a fastening means for securing 95 the parts together. The bracket 18' may be utilized as a stop against which the torch contacts for limiting the rotation of the torch and for holding the same in its initial or inoperative position.

On the lower extremity of the plug 11 is mounted a pinion 20 which meshes with a rack 21 slidably mounted in a bearing 22

formed on the valve casing. The rack is formed on the inner end of a cylindrical rod 23 which by means of a bracket 24 is also suspendingly mounted on the under side of 5 the top plate of the gas stove.

An operating handle 25 is provided on the outer end of the rod and is located at the front of the stove or in any convenient position where it may be within easy reach 10 of an operator.

A coil spring 26 is mounted on the rod adjacent one end thereof and has its opposite ends bearing against the bracket 24 and an adjustable sleeve 27 fixedly mounted on the 15 rod. This spring is provided for normally holding the torch in its inoperative position, and for assisting the return of the torch thereto after the device has been actuated.

Any other suitable means may be employed 20 for effecting the rotation of the torch and the same may be made to rotate completely either to the left or right if desired.

The device when applied to a gas stove is preferably arranged so that the torch when 25 revolved will direct a flame so as to ignite any one of the various burners of which the stove is provided.

In operating the device the handle is pulled outwardly against the action of the 30 spring. The pulling of the handle causes the rack to actuate the pinion and thereby turn the plug which causes full pressure of gas to flow to the torch thereby progressively increasing the volume of the flame 35 flashed outwardly from the tip of the torch which is of sufficient length to reach and ignite the several burners of the stove as the torch is rotated. When the burners have been lighted the torch is then returned, 40 by the action of the coil spring, to its initial position, whereupon by the action of the valve the increased flow of gas to the torch has been materially reduced, thus permitting the maintenance of a small pilot 45 light at the tip of the torch as previously described. If desired, the valve may be grooved so that the flow of gas to the torch may be controlled at any desired point or 50 points in its rotation; thus when the continuous jet method is used and the torch is in its initial or starting position there is only a small flame using therefrom which when the device is actuated, the flame may be made to increase in length and volume 55 until the ignition of the various burners can be effected, such for instance, when the device is to be used on such a gas stove as that indicated in Fig. 10.

In cases where the stove top is provided 60 with a central division bar the torch can be arranged to come to rest under the same and thus be protected from any fluid being spilt over it and extinguishing the flame. When the bar is not provided the tip of the 65 torch can be protected by a small shield or

protector plate extending over each side and top as indicated by 30 in Figs. 7 and 8. The device if desired may be so constructed that any suitable means may be employed for automatically igniting the torch. For 70 instance, when electric ignition is used as indicated in Fig. 6, a spark gap is provided as indicated at 31, which when the torch is revolved electrical contact is made at 32, thus causing a spark to jump across the 75 spark gap and ignite the gas issuing from the tip of the torch. Any suitable electrical energy may be utilized, such as the usual form of batteries or the device may be connected to the usual house circuit if desired, 80 by using a transformer if necessary.

In Fig. 11 I have shown mounted on the tip of the torch a small perforated cylinder 85 35 which may contain platinum sponge or other suitable lighting media. In this form when the pull rod is operated the valve is opened thus permitting the gas to impinge on the lighting media carried in the perforated cylinder, thus causing the ignition 90 of the torch.

The pilot flame may be white, all gas, or a Bunsen flame may be used by the substitution of a torch, as indicated in Fig. 7. A small brush as indicated at 34 in Fig. 9, 95 may also be utilized for cleaning the tip of the torch so as to prevent the accumulation of carbon or other foreign substances thereon.

The brush may be clamped on the bracket used for supporting the valve casing and 100 arranged in the path of movement of the torch so that the tip of the torch may be cleaned at each time the same is turned.

It is obvious that those skilled in the art may vary the details of construction and 105 arrangements of parts without departing from the spirit of my invention and therefore I do not wish to be limited to such features except as may be required by the 110 claims.

What I claim as new is:—

1. In a gas lighting device for gas stoves including a turnable torch and a gas supply pipe therefore, the combination of a valve located in the supply pipe and adapted for progressively increasing the flow of gas to the torch upon the rotation of the torch and burners located at different distances from the axis upon which the torch turns. 115

2. In a gas lighting device for gas stoves including a turnable torch and a gas supply pipe therefore, the combination of a turnable valve located in the supply pipe and provided with a channel and a tapering groove, one communicating with the other for progressively increasing the flow of gas to the torch upon the rotation of the valve and burners located at different distances from the axis upon which the torch turns. 120 125 130

3. In a gas lighting device for gas stoves including a turnable torch and a gas supply pipe therefore, the combination of a valve located in the supply pipe and adapted for 5 gradually increasing the flow of gas through the torch upon the rotation of the torch, a pinion connected to the valve, a pull rod having rack teeth in mesh with the pinion, a spring surrounding the pull rod, and means 10 for effecting the tensioning of the spring when the pull rod is moved in one direction and including a support for the pull rod.
4. A gas lighting device comprising a supply pipe, a turnable torch connected to the 15 supply pipe, means for progressively in-

creasing the flow of gas to the torch as the torch turns, a bracket fixed to the supply pipe, a pull rod to rotate the torch, and means mounted on the torch and arranged in the path of movement of the torch for 20 cleaning the torch upon the turning of the same and burners located at different distances from the axis upon which the torch turns.

In testimony whereof I, affix my signature 25 in presence of two witnesses.

AMANDUS C. ROESSLER.
